[57] CLAIM

The ornamental design for a motor controlled focusing
attachment for telescopes, as shown and described.

DESCRIPTION

FIG. 1 is a perspective view of a motor controlled focusing
attachment for telescopes showing my new
design with a telescope shown in broken lines for illus-
trative purposes only;

FIG. 2 is an enlarged side elevation view thereof;

FIG. 3 is an enlarged top plan view thereof;

FIG. 4 is an enlarged front elevation view thereof;

FIG. 5 is an enlarged rear elevation view thereof.
